Primary Examiner—Lucy Lieberman**Attorney, Agent, or Firm—Young & Thompson****[57] CLAIM**

The ornamental design for a combined spray bottle and cap, as shown and described.

DESCRIPTION

FIG. 1 is a front and side perspective view of a combined spray bottle and cap showing my new design;

FIG. 2 is a front elevational view thereof, the rear elevational view being identical to FIG. 2;

FIG. 3 is a view thereof from the left of FIG. 2, the view from the right of FIG. 2 being identical thereto;

FIG. 4 is a top plan view thereof; and,

FIG. 5 is a bottom perspective view thereof.
